UNITED STATES PATENT OFFICE.

FRANCIS J. FREESE, OF BOSTON, MASSACHUSETTS, ASSIGNOR TO UNITED SHOE MACHINERY COMPANY, OF PATERSON, NEW JERSEY, A CORPORATION OF NEW JERSEY.

SHOE-SEWING MACHINE.

No. 895,623.

Specification of Letters Patent.

Patented Aug. 11, 1908.

Application filed October 7, 1903. Serial No. 176,065.

To all whom it may concern:

Be it known that I, FRANCIS JOSEPH FREESE, a citizen of the United States, residing at Boston, in the county of Suffolk and State of Massachusetts, have invented certain new and useful Improvements in Shoe-Sewing Machines; and I do hereby declare the following to be a full, clear, and exact description of the invention, such as will enable others skilled in the art to which it appertains to make and use the same.

The present invention relates to an improvement in shoe sewing machines and more particularly shoe sewing machines of the curved hook-needle, chain-stitch, wax-thread type of which the commercial Goodyear welt and turn machine is an example. In the Goodyear welt and turn machine after the needle has advanced and the thread finger has formed its bight in the thread between the work and the looper, and after the looper has encircled the needle laying thread in the barb thereof and at the time the needle is retracting and the take-up is falling, giving up thread to the needle on one side and while the thread finger is giving up thread to the needle on the other side, the auxiliary take-up resting upon the thread with spring pressure frequently presses with sufficient pressure upon the thread to cause the thread to reeve around the needle and thus to steal thread from the thread finger, with the result that the loop of thread drawn back by the needle is of insufficient length and is liable to be broken during the passage of the hook of the needle through the stock or reeves through the throat of the needle during a considerable part of its retracting stroke, thereby subjecting the thread to a sawing action through the throat of the needle which tends to injure or abrade the thread and sometimes causes it to break at this point. The operation of the auxiliary take-up in thus stealing thread from the thread finger is objectionable and many efforts have been made to overcome or alleviate such action. The present invention contemplates providing such sewing machine with a device which prevents the auxiliary take-up from falling during a portion of the cycle of operation of the parts, and especially during the first part of the retracting stroke of the needle, which is while the thread finger is giving up thread to the needle. It may also be desirable, under some circum-

stances, to prevent the auxiliary take-up from stealing thread from the needle during the first portion of its advancing movement. These results are accomplished in the illustrated embodiment of the invention by rendering the auxiliary take-up inoperative to take up thread from the time the looper has threaded the needle, while it is retracting and until it has again advanced into engagement with the work.

To the above ends the present invention consists in the devices and combinations of devices hereinafter described.

The accompanying drawing is a sectional side elevation of a portion of a Goodyear welt and turn machine, substantially as illustrated in Letters Patent of the United States No. 412,704, modified in accordance with the present invention.

The needle N, the looper L, thread finger F, the back rest B, the take-up T, and auxiliary take-up t may and preferably will be constructed and operated as in said Goodyear welt and turn machine. Means are provided, however, for preventing the auxiliary take-up from falling during a portion of the cycle of operation of the machine. A slide 1 is mounted in a groove in the head 2 of the machine, a cap plate being provided for maintaining the slide 1 in position. The auxiliary take-up 1 is provided with a shoulder 4 on its lower side which is engaged by the forward end of the slide 1 above referred to. The rear end of the slide 1 is provided with a cam roll 5 which engages the cam surface 6 on the cam disk 7 secured to the main shaft M of the machine.

The operation of the illustrated embodiment of the invention is as follows:—The needle, looper, take-up, back rest, and thread finger operate as described in said patent. The auxiliary take-up which is provided for taking up any slack thread which may exist during the operation of the machine is prevented by the means described from taking up any slack thread from the time the looper has threaded the needle until the needle has retracted and again advanced into engagement with the work. That is to say, the slide 1 is projected forward by the cam 6 after the needle has advanced and the looper has laid the thread in the barb thereof, and engages the shoulder 4 of the auxiliary take-up t and holds the same from falling under the influence of its spring 8, thereby pre-

- venting the auxiliary take-up from stealing thread from the thread finger during the first part of the retracting stroke of the needle and preventing it from falling or stealing thread from the needle during the first part of its advancing stroke, so that the slack thread necessary for the first portion of the retracting stroke of the needle given up by the thread finger will not be stolen by the auxiliary take-up but will be supplied to the needle and so that the auxiliary take-up is prevented from exerting any taking up strain on the thread except when and at the time it should be permitted so to do.
15. The present invention is broad and generic in character and is neither limited to the construction illustrated in the drawings nor to the securing of the entire prevention of the stealing of thread from the thread finger, 20 for beneficial results are obtained by any means acting to prevent the auxiliary take-up from taking up any substantial amount of thread during the first part of the retracting stroke of the needle, or during the time the thread finger is giving up thread to the needle.
25. The present invention is not limited to the embodiment illustrated in the drawing as it may be embodied in other and different forms without departing from the spirit thereof.
30. Having thus described the invention, what is claimed is:—
1. A chain-stitch shoe-sewing machine, having, in combination, a needle, looper, thread finger, take-up, auxiliary take-up, and cam-actuated means for preventing the auxiliary take-up from acting to take up thread during a portion of the cycle of operation, substantially as described.
  2. A chain-stitch shoe-sewing machine, 40 having, in combination, a needle, looper, thread finger, take-up, auxiliary take-up, and

means for preventing the auxiliary take-up from acting during the first part of the retracting stroke of the needle, substantially as described.

45. 3. A chain-stitch shoe-sewing machine, having, in combination, a needle, looper, thread finger, take-up, auxiliary take-up, and means for preventing the auxiliary take-up from acting during the time the thread finger is giving up thread to the needle, substantially as described.

50. 4. A chain-stitch shoe-sewing machine, having, in combination, a needle, looper, thread finger, take-up, auxiliary take-up, and means for preventing the auxiliary take-up from acting from the time the needle begins its retracting stroke until it is again advanced and engages the materials, substantially as described.

55. 5. A chain-stitch shoe sewing machine, having, in combination, a needle, looper, thread finger, take-up, auxiliary take-up, and means for preventing the auxiliary take-up from acting to take up thread during a portion of the cycle of operation, and while the take-up still has capacity for movement to give up thread, substantially as described.

60. 6. A chain-stitch shoe sewing machine, having, in combination, a needle, looper, take-up, auxiliary take-up, and means for preventing the auxiliary take-up from acting to take up thread during the first portion of the advancing movement of the needle, substantially as described.

75. In testimony whereof I affix my signature, in presence of two witnesses.

FRANCIS J. FREESE.
